[57] CLAIM

The ornamental design for a bow hunter's accessory box, as shown.

DESCRIPTION

FIG. 1 is a top perspective view of a bow hunter's accessory box of my new design;

FIG. 2 is a top plan view thereof;

FIG. 3 is a rear elevation of a closed bow hunter's accessory box;

FIG. 4 is a top plan view thereof;

FIG. 5 is a front elevation thereof; and

FIG. 6 is a right side elevation thereof.

The bow hunter's accessory box is used to hold broadheads, spare blades, nocks, a sharpening stone and other accessories required by a bow hunter.
